Primary Examiner—Dominic Simone*Attorney, Agent, or Firm*—Banner & Witcoff, Ltd.[57] **CLAIM**

The ornamental design for a portion of a shoe upper, as shown and described.

DESCRIPTION

FIG. 1 is a perspective view of a portion of a shoe upper showing my new design;

FIG. 2 is a side elevational view of one side thereof;

FIG. 3 is a side elevational view of the other side thereof;

FIG. 4 is a top plan view thereof; and,

FIG. 5 is a front elevational view thereof.

The uneven broken line showing of the stripes on the instep portion and the remainder of the shoe is for illustrative purposes only and forms no part of the claimed design.
